(57) **CLAIM**

The ornamental design for a sport ball as shown and described.

DESCRIPTION

FIG. 1 is a front perspective view of a sport ball showing the claimed design;

FIG. 2 is a front elevation view thereof;

FIG. 3 is a top view thereof; and,

FIG. 4 is a bottom view thereof.

Broken lines in the figures illustrate portions of the sport ball that form no part of the claimed design.

1 Claim, 4 Drawing Sheets
